PESSARY APPLICATOR

Lawrence Schleicher, Los Angeles, Calif.

Application May 11, 1937, Serial No. 141,940

10 Claims. (Cl. 128—127)

This invention relates to a pessary applicator of the general character embodied in my pending application for patent Serial No. 46,797, filed Oct. 25, 1935, and wherein means is provided to effect application of a pessary to the cervix, automatically upon insertion of the pessary into the vagina.

An object of the present invention is to provide a pessary applicator embodying such structural and functional simplification as will reduce its working parts to an absolute minimum without loss of function, and in fact with a distinct improvement in operation by effecting the positive release of the pessary from the applicator in the position necessary for accurate placement of the pessary over the cervix, so as to insure occlusion of the cervix by an impervious barrier.

Another object of the invention is to provide a pessary applicator which is structurally characterized by a few simple parts capable of being manufactured and assembled inexpensively to produce an easily manipulated, durable, and sanitary instrument to which a pessary can be applied for insertion into the vagina and application to the cervix with the utmost ease and dispatch.

A further object of the invention is to provide a pessary applicator embodying means for maintaining the pessary connected to the applicator should the pessary not be released therefrom in the intended manner, whereby to prevent the pessary from being left in the vaginal cavity in an improper position upon withdrawal of the applicator, and enabling the pessary to be withdrawn with the applicator for re-insertion into the vagina.

A still further object of the invention is to provide a pessary applicator including means for displacing tissue on the ceiling of the vaginal cavity during insertion of the pessary and in such relationship thereto as to create sufficient space in the region of the cervix for the reception of the pessary in an effective occluding position when released from the applicator.

With these and other objects in view, the invention consists in the combinations, arrangements and novel functional relationships of elements as set forth in the following specification and particularly pointed out in the appended claims.

In the accompanying drawing, Figure 1 is a schematic view of a portion of the female anatomy, showing the applicator inserted into the vagina preparatory to releasing the pessary over the cervix;

Figure 2 is a plan view of the applicator; Figure 3 is a view in side elevation partly

broken away, and showing the applicator with the pessary supported thereby;

Figure 4 is a view similar to Figure 3 and showing the positions of the working parts at the instant of releasing the pessary.

Referring specifically to the drawing, the present embodiment of the invention comprises an elongated rigid support S providing a handle 10 and a head 11 forming a continuation thereof at one end. The free end of the head is provided with a notch 12 to receive the elastic rim R of a conventional soft rubber pessary P, and the opposite end of the head is provided with a hook-shaped guard and keeper lug 13 which projects from the side 14 of the head and co-acts therewith to define a recess 15 open towards the free end of the head to receive the rim R of the pessary at a point diametrically opposite to the point at which the rim co-acts with the notch 12.

The head is provided with a pocket 16 freely receiving a cervix-actuated pessary latching or holding member in the form of a latch arm 17 which is mounted at one end by a pin 18 adjacent the free end of the head, for pivotal movement to occupy holding and releasing positions as shown respectively in Figures 3 and 4. A coil spring 19 bearing against the bottom wall 20 of the pocket 16, and seating in a socket 21 in the arm, urges the latter to its holding position wherein the free end of the arm is adapted to engage the lug 13 to limit movement of the arm under the action of the spring.

The free end of the arm is oppositely beveled at 22—22 to provide an end edge 23 which spans the open side of the recess 15, and is recessed at 24 to provide a bill 25, all for the purpose of facilitating and insuring release of the pessary from the arm during the operation of the invention which is as follows:

The pessary P is applied to the head 11 by a movement of its rim R across the exposed surface 26 of the arm 17 towards the recess 15, with sufficient pressure upon the arm to depress or move the latter to its releasing position so as to enable the rim to enter the recess 15 and be confined therein by the end edge 23 which spans the recess upon the return of the arm to its holding position under the action of the spring 19.

The rim of the pessary is now stressed into elongated form and seated in the notch 12 so that the latter will co-act with the arm 17 to releasably retain the pessary in its stressed position shown in Figure 3 and in broken lines in Figure 2, for insertion into the vagina.

The handle 10 is now grasped, and the head

11 with the pessary applied thereto inserted into the vagina, it being noted that the rounded and laterally offset portion 27 of the handle functions to press against the floor of the vagina, and 5 sufficiently enlarge the latter for diametrically opposed points of the rim R to be correlated respectively with the posterior cul-de-sac A and the anterior cul-de-sac B. Thus upon shifting the head laterally towards the cervix, the latter 10 will co-act with the surface 26 of the arm through the intervening membranous wall of the pessary, to move the arm to its releasing position shown in Figure 4, whereby to effect the instantaneous release of the pessary from the end edge 23 and 15 from the notch 12 as the energy of the stressed rim is utilized in tending to restore the rim to its normal shape in sealing contact with the tissues.

The extreme simplicity of the mode of operation to positively and accurately release the pessary automatically will be readily appreciated, as it will be evident that it is only necessary for the end edge 23 of the arm to move a short distance into the pocket 16 and thus permit the 20 rim of the pessary to be instantly withdrawn from the recess 15 and entirely cleared from the arm, under the tendency of the rim to return to its normal circular form. The small area presented by the end edge 23 of the arm to the 25 pessary rim, and the inclination of this edge away from the rim in a direction towards the bill 25, overcomes any tendency of the rim to stick or become jammed in a manner which would 30 adversely affect the complete freeing of the pessary from the instrument, whereby to practically eliminate the possibility of an ineffective positioning of the pessary over the cervix.

It is to be noted that should the rim of the pessary become disengaged from the notch 12 40 as a result of improper insertion of the instrument into the vagina, or from any other cause, the keeper lug 13 will co-act with the arm 17 to maintain the pessary connected to the instrument for withdrawal therewith preparatory to a 45 second insertion, rather than leave the pessary in an ineffective position in the vagina when the instrument is withdrawn therefrom.

Furthermore, it will be noted that the keeper lug also functions to displace tissue in advance 50 thereof on the ceiling of the vaginal cavity during insertion of the instrument into the vagina, so as to create sufficient space therein for the 55 reception of the pessary in an effective occluding position when released from the instrument.

What is claimed is:

1. An applicator of the class described comprising a support insertable into the vagina; a cervix-actuated member movably mounted on the support to occupy holding and releasing positions; means on the support co-actable with one end of said member to retain a pessary on the support; means for urging said member to holding position; and means on the support disposed to co-act with said end of the member in preventing disengagement of the pessary therefrom so long as the member occupies holding position.
2. An applicator of the class described comprising a support insertable into the vagina; a cervix-actuated member movably mounted on the support to occupy holding and releasing positions; means on the support co-actable with one end of said member to retain a pessary on the support; means for urging said member to holding position; and means on the support defining

a keeper for the member in its urged direction and co-actable with the member in preventing disengagement of the pessary therefrom when the member occupies holding position.

3. An applicator of the class described comprising a support insertable into the vagina; a cervix-actuated member movably mounted on the support to occupy holding and releasing positions; means on the support co-actable with one end of said member to retain a pessary on the support; means for urging said member to holding position; and a lug on the support co-acting therewith to define a recess receiving the pessary rim when correlated with said end of the member; said lug being disposed to limit the movement of the member in its urged direction and co-actable with the member in preventing disengagement of the pessary therefrom when the member occupies holding position.

4. An applicator of the class described comprising an elongated support having a pocket therein at one end; a cervix-actuated latch arm operating in said pocket and pivoted on the support adjacent said one end thereof for movement to occupy holding and releasing positions; means on the support co-actable with the free end of said arm when in holding position, to retain a pessary on the support; and means for urging the arm to holding position.

5. An applicator of the class described comprising an elongated support having a pocket therein at one end; a cervix-actuated latch arm operating in said pocket and pivoted on the support adjacent said one end thereof for movement to occupy holding and releasing positions; means on the support co-actable with the free end of said arm when in holding position, to retain a pessary on the support; means for urging the arm to holding position; and a hooked stop lug on the support disposed to limit movement of the arm in its urged direction and co-actable with the arm when in holding position to prevent disengagement of the pessary therefrom.

6. An applicator of the class described comprising a support insertable into the vagina and having a pocket therein; a cervix-actuated member operating in the pocket and pivotally mounted at one end on the support for movement to occupy a holding position wherein its other end projects from the pocket, and a releasing position wherein said other end is received in the pocket; means on the support co-actable with said other end of the member to retain a pessary on the support when the member occupies holding position; and means for urging the member to holding position.

7. An applicator of the class described comprising a support insertable into the vagina; co-acting means on the support including a movably mounted latching member for holding a pessary on the support; means for urging said member to latching position; and a keeper on the support co-actable with said member when in latching position, to prevent disengagement of the pessary therefrom.

8. An applicator of the class described comprising a support insertable into the vagina and having means adapted to be engaged by the rim of a pessary; a latching member movably mounted on the support and adapted to be engaged at one end by the rim of the pessary for co-action with said means in holding the pessary on the support; means for urging said member to latching position; and a stop on the support co-actable

with said member when in latching position to limit movement of the member by the urging means.

9. An applicator of the class described comprising a support insertable into the vagina; co-acting means on the support adapted to be engaged by the rim of a pessary at opposed points to retain the pessary in a position for insertion into the vagina; means for releasing the pessary 5 from said co-acting means; and means for maintaining the pessary connected to the support at one of said points should the pessary become disengaged from the respective one of said co-acting means at the other of said points during the 10 inserting operation whereby to enable the pessary 15 to be withdrawn from the vagina by the support.

10. An applicator of the class described comprising a support insertable into the vagina; co-acting means on the support adapted to be engaged by the rim of a pessary at opposed points to retain the pessary in a position for insertion 5 into the vagina; cervix-actuated means for releasing the pessary from said co-acting means; and means correlated with one of said co-acting means for maintaining the pessary connected to the support should the pessary become disengaged 10 from the other of said co-acting means without a releasing operation of the cervix-actuated means, whereby to compel the pessary to be withdrawn from the vagina by the support.
